UNITED STATES PATENT OFFICE

2,517,175

CASH DRAWER OR THE LIKE

Fredrick J. Bremer, Hamilten, Ohio, assignor to
The Mosler Safe Company, Hamilton, Ohio, a
corporation of New York

Application January 23, 1947, Serial No. 723,787

11 Claims. (Cl. 109—47)

1

This invention relates to cash drawers and similar devices for receiving money and other valuables, and pertains particularly to means for effecting closing and locking the cash drawer from a remote point.

One of the objects of the present invention is to provide means for temporarily maintaining a cash drawer or the like in open position, said means being releasable for initiating closing of the drawer from a point on or near the drawer, or from a remote point, and for automatically locking the drawer simultaneously with the closing thereof when the closing is effected from said remote point.

Another object of the invention is to provide means for closing and locking cash drawers and the like from a remote point, and means associated therewith for insuring a delay between operation of a releasing means and the actual release of the drawer, whereby valuables may be effectively safeguarded against unauthorized access.

A further object is to provide an improved and most effective closing and locking mechanism for a cash drawer or similar device which is simple in construction and effective in operation and by which the cash drawer may be locked by someone remote from the cash drawer and without movement of, or danger to, the cashier.

These and other objects and advantages are attained by the means described in the following specifications and illustrated upon the accompanying drawings, in which:

Fig. 1 is a perspective view of a typical form of cash drawer embodying the present invention, the drawer section being withdrawn.

Fig. 2 is a fragmentary vertical sectional view through the device of Fig. 1, illustrating means for maintaining the drawer in open position for the convenience of the cashier in making change.

Fig. 3 is a fragmentary sectional view showing the hold-open mechanism as applied to the rear of the cash drawer.

Fig. 4 is a vertical sectional view showing the mechanism for controlling the locking of the drawer, as applied to the rear inner wall of the drawer housing.

Fig. 5 is a horizontal sectional view of the device of the invention, showing the drawer in a normally closed position.

Fig. 6 is a diagrammatic illustration of the electrical connections adapted for controlling operation of the mechanism illustrated in Fig. 5.

In order to safeguard cash and other valuables effectively, it is not only necessary to provide means which prevent unauthorized access thereto when the cashier or other attendant is not present, but it is also necessary under some circumstances to prevent immediate access to the valuables even by an authorized agent possessing

a proper key, as for instance, when the agent as well as the cashier may be ordered, under threat of bodily harm, to open the cash drawer or safe.

Accordingly, means heretofore have been provided for locking a cash drawer from a remote point, utilizing a push-button switch on the floor or under a counter, operable by the foot of a clerk remote from the cash drawer, when a bandit enters the premises. Therefore the drawer was locked without movement of the cashier or anyone near the cash drawer, thus lessening the danger of violence from an armed bandit who might be tempted to shoot at the first suspicious move of store attendants. If the cashier was forced to unlock the cash drawer, access was not possible until expiration of a predetermined interval of time, say fifteen to thirty minutes, as determined by a timing device intended to interpose the element of delay in executing the theft or burglary.

Devices operating generally in the manner above recited are covered in U. S. Patent No. 2,145,314, granted January 31, 1939, to J. J. Murtaugh, Jr. In that device, the cash drawer was constantly urged toward the closed position by spring means, so that the cashier was required to hold the drawer open while making change. Some cashiers found it more convenient to wedge the drawer in the open position, than to open it at each change-making operation. As the result of such practice, the function of the remotely controlled locking mechanism was defeated, since the improvised wedge used in holding the drawer open prevented rapid closing of the drawer in an emergency. Consequently, operation of the locking mechanism while the drawer was open proved ineffective.

In the device of the present invention, for convenience in making change, means have been provided for holding the drawer open against the pull of the springs which normally urge the drawer to a fully closed position. After change has been made, the cashier simply manipulates a thumb lever on the front of the drawer, which, through associated linkage, elevates a plunger which permits closing of the drawer. In association with the hold-open plunger is electrical means for lifting the plunger simultaneously with the operation of the automatic latch plunger for locking the drawer closed by remote control means. Thus it will be seen that if an unauthorized person, such as a bandit, should enter the premises while the cash drawer is held open with the hold-open plunger, a clerk or other attendant near to or remote from the cash drawer need only to press a button to automatically release the hold-open plunger to close the drawer and simultaneously engage the latch plunger to lock the drawer closed against unauthorized access thereto. In order to release the drawer, the pro-

cedure is substantially the same as that outlined in Patent No. 2,145,314. The drawer, of course, may be provided with ordinary locking means, apart from the automatic electrical locking means, for locking and unlocking the drawer at will to enable authorized persons to have access thereto without the inconvenience and delay incident to the use of the timing device.

Referring to Fig. 1, the character 12 indicates a cash drawer which is supported in a housing 13 which may be of any suitable construction and may comprise part of a safe, counter, or other structure, if desired. The housing shown embodies a top 15, sides 16 and 17, a bottom 18, a back 19, and a front 20. Supporting means on the bottom may be provided, as indicated by the metal strips 21 and 22 adjacent the front and back, respectively, of the housing. The corners of the housing may be reinforced by angle members 23 extending along the marginal portions of said housing to provide a sturdy theft-resistant construction.

The drawer 12 is supported within the housing on rollers 25 mounted on fixed studs 26 projecting inwardly from the side walls 16 and 17. Roller bearings 27 may be provided insuring smooth sliding movement of the drawer so that it will close readily and move easily to its fully closed position. Plates 28, in abutting engagement with the inner faces of the side walls 16 and 17, and suitably attached thereto, as by welding, provide a rigid mounting for the studs 26. Supporting rails 29 extend along the sides 30 and 31 of the drawer 12 and bear upon the rollers 25 to support said drawer, whereas angle bars 32 project from the sides of the cash drawer beneath the rollers 25 for guiding the drawer in its sliding movement. The drawer itself may be of any usual construction and may be divided into sections by partitions 33 or the like for receiving coins and bills, or may be otherwise arranged for the purpose of receiving other valuable matter, such as jewelry and precious stones.

Outward movement of the drawer is limited by a catch 34 pivoted at 24 on each side of the drawer, and positioned to engage a fixed stop member 35 inwardly projecting from the walls 16 and 17 near the front of the housing, while inward movement of the drawer is limited by a projecting flange 36 on the drawer front 37 which engages a downwardly projecting bolt engaging flange 38 adjacent the front of the housing, as shown in Fig. 2. The drawer is normally urged to the fully closed position by means of springs 39 which are anchored at one end to inwardly projecting lugs 40 secured to the housing back 19, and anchored at the opposite end to similar lugs 41 secured to the laterally extending flanges 42 of the drawer front 37. Guards 43 may be provided for the springs, said guards extending along the sides of the drawer as indicated, and adapted to enclose the springs in dust-proof relation therewith. To remove the drawer bodily from the housing, it is necessary to disconnect the springs 39 and to depress the ends 44 of the pivoted catches 34, to release them from the stops 35.

In order to insure a cushioned closing of the drawer at all times against the force of springs 39, an air check 45 has been provided. As shown in Fig. 5, the cylinder 46 of the air check is suitably secured to the inner wall of side 17 as at 54, while the rod 47 thereof is secured to the flange 42 of the drawer front 37. The air check

45 may be of any standard type available on the market.

An ordinary key lock 48 may be carried by the drawer for upwardly projecting a bolt 49 against the inner face 50 of the bolt engaging flange 38 on the housing front 20. Any suitable lock construction may be used in this location or elsewhere for enabling the cashier or other authorized agent to lock and unlock the drawer at will so that it may be instantly available for use under ordinary circumstances, as for instance, the cashier may lock the cash drawer during the lunch period. However, in order to further safeguard the contents of the drawer under unusual circumstances, as in the event of a hold-up, supplemental locking means are provided which are operable to prevent opening of the drawer and which may preferably be actuated from a remote point for locking the drawer, as will be herein-after described.

In the construction illustrated, the bottom 48' of the cash drawer 12 is provided with a rearwardly extending shelf portion 49' having a latch receiving aperture 50' positioned to receive a latch plunger 51 depending from the vertical armature 52 of a solenoid 53. A mounting plate 55, which may be anchored to the rear wall 19 of the casing by means of screws 56 or otherwise, serves to maintain the solenoid 53 in a vertical position. Projecting from the mounting plate 55 is the latch plunger guide bracket 57, bored as at 58 for the freely slideable reception of the latch plunger 51, which is gravity actuated to drop into the aperture 50' when released, thereby to lock the drawer closed. The latch plunger 51 is supported or held out of its latching position by means of a horizontal pin or dog 59, which is urged toward the notch 60 of the latch plunger 51 by the spring 61. The pin or dog 59 is attached at one end to the forward end of the armature 62 of solenoid 63, said solenoid being horizontally mounted on the mounting plate 55. A lateral extension 65 of the guide bracket 57 is bored as at 66 for the slideable reception of the retainer pin or dog 59. Thus it will be seen that the latch plunger 51 is held out of engagement with the latch receiving aperture 50' as long as the pin 59 is urged forward into the latch plunger notch 60 by the force of spring 61. When the coil of solenoid 63 is energized, it serves to retract its associated armature 62, carrying with it the attached retaining pin or dog 59, permitting the latch plunger 51 to drop into locking engagement with the latch receiving aperture 50'.

The cash drawer will thus be locked against opening even though the bolt 49 of lock 48 is withdrawn. Furthermore, any efforts to force the drawer open will cause only a forward pull on the lowermost portion of the latch plunger 51 which is firmly held in the rigid latch plunger guide bracket 57. Thus it is apparent that no strain will be placed upon the latch operating mechanism or the solenoids which actuate it, so that these parts will be not be damaged by tampering with the drawer.

In order to effect opening of the cash drawer, it is necessary to energize the coil of the solenoid 53. When this takes place, the associated armature 52 is retracted into the solenoid, at the same time elevating the latch plunger 51 out of engagement with the aperture 50' in the drawer portion 49'. As the plunger 51 is elevated, the retainer pin 59 is urged into the latch plunger notch 60 by the force of spring 61.

As pointed out hereinbefore, it is of advantage to delay the retraction of the latch plunger 51 following the emergency. A lock 67 of any suitable construction is provided in the front wall 20 of the housing, projecting therethrough as shown in Fig. 2. The cylinder 68 of the lock controls a bolt 69 which normally extends downwardly into position to be engaged by a radial arm 70. This arm is to be driven or swung by a clockwork indicated generally by 71. As shown, the arm 70 is fixed to a rotary shaft 72 of the clock mechanism 71 for horizontal movement thereon. Upon retraction of the lock bolt 69, arm 70 is released and slowly rotated clockwise by the clock mechanism, for ultimately closing an electric switch 73. As illustrated by Fig. 5, the arm 70 in its rotating movement first engages the insulated member 75 and thereafter moves this member into engagement with a movable electric contact 76 which in turn strikes the fixed contact 77 to complete a circuit through the solenoid 53. When this solenoid is energized, the latch plunger 51 is elevated out of engagement with the aperture 50' by reason of its connection with the armature 52, thus releasing the drawer. As the latch plunger 51 is raised in the plunger guide bracket 57, the notch 60 on the latch plunger is brought into register with the forwardly impelled retainer pin or dog 59, thereby to maintain the latch plunger 51 in its elevated position until again released by subsequent retraction of pin 59. Switch 73 may be of a type other than is illustrated.

After the drawer has been unlocked, and pulled to open position, the clerk or cashier reaches up within the housing, grasps the radial arm 70 and restores it to the normal position, shown in Figs. 2 and 5, at which position it is held ready for subsequent action, by means of the lock bolt 69. In so moving the arm 70 to the normal position of restraint, the operating spring of the clockwork is re-wound. It should be understood that the time required for arm 70 to move from the normal position of Fig. 5, to the position at which it closes the switch contacts 76-77, may be governed in accordance with the wishes of the manufacturer or user of the device. The delay period usually will consume some fractional part of an hour, or sufficient time to discourage a bandit from waiting until the time lock releases the drawer.

In addition to the two solenoids 53 and 63 which actuate the emergency locking mechanism, a third solenoid 78 has been introduced for actuating a mechanism which automatically releases the drawer for movement from a forcibly-held open position, to a closed position, said solenoid 78 being preferably connected to the same electrical circuit which energizes solenoid 63, so that the action of closing the cash drawer and locking it is simultaneous.

As hereinbefore explained, it was formerly the practice of clerks or cashiers to wedge a drawer of this type open against the pull of the springs 39 in order to be able to use both hands in making change, the wedging means being a stick of wood, a piece of cardboard, or whatever material was convenient to serve the purpose. This practice, of course, made the locking mechanism ineffective in case of emergency. The present invention definitely provides means for holding the drawer open against the pull of the springs 39, without impairing the emergency locking function. Such means may comprise a riding plunger 79, as shown in Figs. 2 and 3, vertically mounted on the rear wall 81 of the drawer. Normally this

plunger 79 rides on the bottom wall 18 of the drawer casing or housing 19 as the drawer is opened and closed. When the drawer is withdrawn by means of the handle 82 to its full extent, plunger 79 gravitationally drops into the aperture 80 bored through the bottom wall 18 and its contiguous support member 21, thereby to hold open the cash drawer against the pull of the springs 39. When the clerk or cashier wishes to close the drawer, he merely manipulates the thumb lever 83 on the front of the drawer which, through link 85, bell crank lever 86, and pin 87 in the plunger 79, elevates the said plunger to permit closing of the drawer. Extending along one side of the drawer is the rod 88, one end of which protrudes through a lateral flange 42 of the drawer front. Fixed to the forward end of the rod is the thumb lever 83. The opposite end of the rod is bent downwardly and outwardly to form a crank 89, the outward horizontal end 90 being pivotally associated with one end of the link 85. The opposite end of the link 85 is pivotally joined to the upper end of the vertical bell crank arm 91. A clamp 92, suitably secured to the side wall of the cash drawer, is provided for supporting the lever rod 88 adjacent the crank end 89.

Abutting against the outer face of the drawer back 81 and substantially centrally thereof is the plunger guide plate 93, including a vertical portion 95, which may be fixed to the drawer back by suitable means, such as welds, screws, or the like. The plate 93 is bent outwardly, downwardly and inwardly at substantial right angles, to form upper and lower plunger guide portions 96 and 97 respectively, and a vertical bell-crank pivot plate support 98. The lower plunger guide portion 97 may be welded or otherwise secured to the drawer bottom extension 49. The bell crank pivot plate, which is indicated at 99 and which may be bolted or otherwise fixed to the pivot plate support portion 98 of the plunger guide plate 93, extends beyond the vertical edge of the support portion 98 a sufficient amount to support the bell-crank pivot 100. Guide holes 101 for the plunger 79 are bored through the horizontal portions 96 and 97 of the plunger guide plate 93 and through the drawer bottom extension 49, said holes being in axial alignment and in register with the aperture 80 when the drawer is withdrawn to its full extent.

As shown in Fig. 3, the horizontal arm 102 of the bell crank 86 abuts the plunger pin 79 at its lower side when the plunger is within the aperture 80, so that when the link 85 is shifted to the left, as viewed in Fig. 3, by means of the thumb lever 83, the bell crank 86 will elevate the plunger 79 out of engagement with aperture 80, thereby causing the drawer to close through the pulling action of springs 39. As pointed out earlier, the lower tip of the plunger 79 rides on the bottom wall 18 of the housing as the drawer is opened and closed.

As indicated upon Fig. 3, the solenoid 78 is vertically supported against the plunger guide plate 93, the axis of the solenoid coil being in alignment with the guide holes 101. The upper end 102 of the vertical plunger 79 is connected to the lower end of the solenoid armature 103. A stop 105 is provided on plunger 79 to limit its downward travel, said stop abutting the upper horizontal portion 96 of the plunger guide plate 93 when the cash drawer is in open position. When the coil of solenoid 78 is not energized, the armature 103 is adapted for free vertical

reciprocation therein, as the plunger 79, connected to said armature, is gravitationally dropped into or manually elevated out of the aperture 80. When the solenoid 78 is energized, the armature 103 is retracted and carries with it the connected plunger 79, thereby permitting the drawer to close without any manual effort.

Thus it will be seen that if a hold-up should occur while the drawer is open, the pressing of a push-button energizes the solenoid 78 to release the drawer for rapid movement to closed position, while at the same time the solenoid 63 is energized to retract the pin 59 which permits latch plunger 51 to drop into the latch receiving aperture 50, thus locking the drawer against unauthorized entry thereto. The drawer may be opened only after a predetermined interval of time by the means hereinbefore disclosed.

Since the two solenoids which act to close and lock the cash drawer are on the same electrical circuit, means for maintaining this circuit is provided by the flexible electric cord 106, suspended between suitable connections, such as the outlet receptacle 107 on the rear wall of the housing 13 and a similar receptacle 108 on the rear wall 81 of the drawer, as shown in Fig. 5. Thus the circuit between the two solenoids 63 and 78 is maintained as the coiled cord 106 expands and contracts upon opening and closing of the drawer.

The electrical wiring diagram is shown in Fig. 6. Push button switches, any number of which may be used in connection with the device and located at suitable points remote from the cash drawer, are indicated at 109. The feed wires which furnish the current for energizing the solenoids are indicated at 118 and 112, the solenoid 53 being energized when the timer switch 113 is closed by the clock mechanism 11. Conductors 113 and 115 supply current to the solenoids 63 and 78 when any one of the push button switches 109 is closed, the characters 116 and 117 indicating the wires to which the push buttons may be connected. Conductors 118 and 119 connect the coil of solenoid 63 to wires 113 and 115 within the receptacle 107, whereas those at 120 and 121 connect the coil of solenoid 78 in the same circuit, by way of receptacle 108. As shown upon Fig. 5, the necessary wires may enter the housing 13 through an outlet box or receptacle 118 attached to the rear wall 19 of the housing.

While the construction herein illustrated and described is designed particularly for use in connection with cash drawers and similar devices, it will be apparent that the invention may be embodied in other types of apparatus or mechanism, and that various forms of plunger operating means may be employed without departing from the spirit of the invention. It will also be apparent that the switches 109 may be used to actuate the plunger controlling solenoids associated with any number of cash drawers and the like so that all of the drawers in a bank or other institution may be closed and locked simultaneously by an operator at a remote point and without manipulation by a cashier or others who would be in danger of injury should they attempt to make such a move. It should therefore be understood that the form of the invention herein illustrated and described is intended to be representative of a typical embodiment of the invention and is not intended to limit the scope thereof.

What is claimed is:

1. In combination with a drawer, a housing including means supporting the drawer for movement to closed position within the housing, and

5 to open position partly outside the housing, means operative to propel the drawer to the closed position, means to hold the drawer in open position affording free access to the interior of the drawer, means for actuating said holding means to release the drawer, emergency means remotely controlled for releasing said holding means and placing the drawer under the control of the propelling means, to return the drawer to closed position, and a latch operative only upon actuation of the emergency means, to fix the drawer in said closed position.

10 2. In combination with a drawer, a housing including means supporting the drawer for movement to closed position within the housing, and to open position partly outside the housing, means operative to propel the drawer to the closed position, means to hold the drawer in open position affording free access to the interior of the drawer, means for actuating said holding means to release the drawer, emergency means remotely controlled for releasing said holding means and placing the drawer under the control of the propelling means, to return the drawer to closed position, a latch operative only upon actuation of the emergency means, to fix the drawer in said closed position, and time-delay means precluding normalizing of said latch until expiration of a predetermined time interval.

15 3. In combination with a drawer, a housing including means supporting the drawer for movement to closed position within the housing, and to open position partly outside the housing, spring means tending always to restore the drawer to the closed position, a latch to hold the drawer in open position against the force of the spring means, manually operated means for actuating said latch to release the drawer, electric means remotely controlled for actuating said latch and thereby releasing the drawer for movement to closed position under the power of said spring means, and a second latch normally inoperative, and means operative simultaneously with operation of said electric means for placing the second latch in condition to lock the drawer in the closed position upon return of the drawer to the closed position following operation of said electric means.

20 4. In combination with a drawer, a housing including means supporting the drawer for movement to closed position within the housing, and to open position partly outside the housing, spring means tending always to restore the drawer to the closed position, a latch to hold the drawer in open position against the force of the spring means, manually operated means for actuating said latch to release the drawer, electric means remotely controlled for actuating said latch and thereby releasing the drawer for movement to closed position under the power of said spring means, a second latch normally inoperative, and means operative simultaneously with operation of said electric means for placing the second latch in condition to lock the drawer in the closed position upon return of the drawer to the closed position following operation of said electric means, and time-delay means precluding return of the second latch to its aforesaid normally inoperative position.

25 5. In combination with a cash drawer, a housing including means supporting the drawer for movement to open and closed positions, means for constantly urging the drawer to closed position, a latch for holding the drawer in open position against the force of the urging means,

a second latch for locking the drawer in closed position, manually operated means for actuating the first mentioned latch to release the drawer whereby the urging means closes the drawer, and electrically operable means for actuating said first mentioned latch to drawer release position and positioning said second mentioned latch to effect locking of said drawer when the drawer reaches closed position.

6. In combination with a cash drawer, a housing including means supporting the drawer for movement to open and closed positions, means for constantly urging the drawer to closed position, a latch for holding the drawer in open position against the force of the urging means, a second latch for locking the drawer in closed position, manually operated means for actuating the first mentioned latch to release the drawer, whereby the urging means closes the drawer, electrically operable means for actuating said first mentioned latch to drawer release position and positioning said second mentioned latch to effect locking of said drawer when the drawer reaches closed position, and means for actuating the second latch to drawer unlocking position when the drawer is to be opened.

7. In combination with a cash drawer, a housing including means supporting the drawer for movement to open and closed positions, means for constantly urging the drawer to closed position, a latch for holding the drawer in open position against the force of the urging means, a second latch for locking the drawer in closed position, manually operated means for actuating the first mentioned latch to release said drawer to closed position, electrically operable means for actuating said first mentioned latch to drawer release position and positioning said second mentioned latch to drawer locking position, time delay mechanism for actuating said second mentioned latch to open position when a predetermined length of time has elapsed after operation thereof has been initiated, and means for initiating operation of said time-delay mechanism.

8. In combination with a cash drawer, a housing including means supporting the drawer for movement to open and closed positions, means for constantly urging the drawer to closed position, a latch for holding the drawer in open position against the force of the urging means, a second latch for locking the drawer in closed position, manually operated means for actuating the first mentioned latch to release said drawer to closed position, electrically operable means for actuating said first mentioned latch to drawer release position and positioning said second mentioned latch to effect locking of said drawer when said drawer reaches closed position, a lock, time delay mechanism under control of said lock for actuating said second mentioned latch to drawer unlocking position when a predetermined length of time has elapsed after operation thereof has been initiated, and means for initiating operation of said time delay mechanism by operation of said lock.

9. In combination with a cash drawer, a housing including means supporting the drawer for movement to open and closed positions, springs constantly urging the drawer to the closed position, a latch for holding the drawer in open position against the force of the springs, a second latch for locking the drawer in closed position, manually operated means for actuating the first

mentioned latch to release the drawer, whereby the springs close the drawer, a catch for holding said second mentioned latch in disengaged position, a solenoid adapted to actuate said first mentioned latch to drawer release position, a second solenoid adapted to actuate said catch to position the second mentioned latch to effect locking of the drawer when the drawer reaches closed position, means for energizing said solenoids for actuating said first mentioned latch and said catch, whereby the drawer is released to close and is latched shut upon energizing of said solenoids, a third solenoid inside said housing and adapted to disengage said second mentioned latch and re-energize said catch, time delay mechanism energizing said third mentioned solenoid, when a predetermined length of time has elapsed after operating thereof has been initiated, and means for initiating operation of said time delay mechanism.

10. In combination with a cash drawer, a housing including means supporting the drawer for movement to open and closed positions, means for constantly urging the drawer to closed position, a latch for holding the drawer in open position against the force of the urging means, manually operated means for actuating said latch to release the drawer to closed position, a second latch for locking said drawer in closed position, means for holding said locking latch in drawer unlocking position, and emergency latch control means which actuates the first mentioned latch to release the drawer to closed position and conditions the locking latch to lock the drawer when the drawer reaches closed position if the drawer is open and actuates the locking latch to locking position if the drawer is closed.

11. In combination with a cash drawer, a housing including means supporting the drawer for movement to open and closed positions, means for constantly urging the drawer to closed position, a latch for holding the drawer in open position against the force of the urging means, manually operated means for actuating said latch to release the drawer to closed position, a second latch for locking said drawer in closed position, means for holding said locking latch in drawer unlocking position, emergency latch control means which actuates the first mentioned latch to release the drawer to closed position and conditions the locking latch to lock the drawer when the drawer reaches closed position if the drawer is open and actuates the locking latch to locking position if the drawer is closed, time delay mechanism for actuating said locking latch to open position when a predetermined length of time has elapsed after operation thereof has been initiated, and means for initiating operation of said time delay mechanism.

Certificate of Correction

Patent No. 2,517,175

August 1, 1950

FREDRICK J. BREMER

It is hereby certified that error appears in the printed specification of the above numbered patent requiring correction as follows:

Column 8, line 42, strike out the word "and" before "a"; column 9, line 43, for "his" read *has*; and that the said Letters Patent should be read as corrected above, so that the same may conform to the record of the case in the Patent Office.

Signed and sealed this 7th day of November, A. D. 1950.

[**SEAL**]

THOMAS F. MURPHY,
Assistant Commissioner of Patents.
